Application November 2, 1951, Serial No. 254,567

Claims priority, application Great Britain
January 11, 1951

3 Claims. (Cl. 179—115.5)

This invention relates to microphones.

One of the objects of the present invention is to provide a microphone which is largely, if not wholly, non-responsive to background noises, that is to say, noises emanating from a relatively distant source, but which is suitable for transmitting sounds applied to the microphone from a close source.

Microphones fulfilling this object can be advantageously employed in aircraft, in vehicles with a high ambient noise level, in crowded surroundings and under noisy conditions in general.

According to the present invention there is provided a microphone comprising a plane diaphragm, both faces of the diaphragm being substantially freely accessible to the surrounding air over substantially the whole peripheral extent of the diaphragm, means for supporting the diaphragm so that the latter can vibrate, a coil supported from the diaphragm to move in correspondence with the vibration of the diaphragm, and means for establishing a magnetic field whereby movement of the coil in the field causes an electromotive force to be induced in the wires of the coil, the arrangement being such that sound waves from a relatively distant source cause substantially no vibration of the diaphragm and sound waves from a relatively close source not in the plane of the diaphragm cause vibration of the diaphragm.

We are aware that it has been previously proposed in United States Patent No. 2,350,010 to provide a microphone having a peripherally supported diaphragm mounted within a housing such that the diaphragm divides the housing into two compartments, there being two openings in the housing, one leading into each compartment so that if vibrations or sound waves are applied equally at the housing openings, the waves will act equally upon the diaphragm to prevent vibration thereof. When, however, sound waves are emitted in close spaced relation to, and are directed into, one of the openings of the previously proposed microphone, the diaphragm vibrates, whereby a coil is moved correspondingly in a magnetic field and an electromotive force is generated in the wires of the coil.

In the previously proposed microphone, the housing and openings constitute means for directing sound waves initiated at a distance to impress these waves upon the two opposite faces of the diaphragm in substantially identical phase and amplitude. In the microphone according to the present invention there is no such means for directing the sound waves, the diaphragm being substantially freely accessible to the surrounding air over substantially the whole peripheral extent of the diaphragm.

For a better understanding of the invention and to show how the same may be carried into effect, reference will now be made to the accompanying drawings, in which:

Figure 1 is a cross-sectional elevation of a microphone having a centrally supported diaphragm;

2

Figure 2 is a plan view of the magnet housing of the microphone shown in Figure 1, and

Figure 3 is a cross-sectional elevation of a microphone having a peripherally supported diaphragm.

5 The microphone shown in Figure 1 has a pot-type magnet comprising a permanent magnet 1 having a centrally disposed pole-piece 2 secured thereon. A magnet housing 3 of hollow cylindrical form closed at the lower end by a base plate 3A encloses the magnet 1 and pole-piece 10 2. The pole-piece 2 is disposed within a circular opening in the top of the housing 3, whereby an annular air gap 4 is formed between the pole-piece 2 and the housing 3. The iron circuit of the magnet consists of pole-piece 2, magnet 1, base plate 3A and housing 3, the pole-piece 2 being of opposite polarity to that portion of the housing adjacent the pole-piece.

15 A coil 5 disposed in the air gap 4, is wound on a former 6, which latter is supported from a diaphragm 7. The diaphragm 7 is secured on the pole-piece 2 by means of 20 an upstanding stud 8 which is passed through the centre of the diaphragm 7 and has a nut 9 threaded thereon. A thick washer 10 is interposed between the diaphragm 7 and the pole-piece 2, and a washer 11 is interposed between the nut 9 and diaphragm 7.

25 A plurality of recesses 12 (Figure 2) are formed around the upper outer periphery of the housing 3 to ensure that the underside face of the peripheral edge portion of the diaphragm is freely in contact with the surrounding air. The recessed top of the housing 3 has a castellated 30 appearance.

35 The diaphragm is protected against damage by a perforated cover 13, the bottom of which is secured to the side wall of the housing 3. It is to be understood that the cover 13 allows sound waves to be transmitted freely therethrough and in no way serves as a guide for directing sound waves onto the two opposite faces of the diaphragm 7.

40 A washer 15 is provided within the housing 3 for closing the cavity between the housing 3 and the magnet 1.

The diaphragm 7 has a plurality of holes 16A therethrough, the holes being disposed in a ring around the washer 10.

45 The microphone shown in Figure 3 is similar to Figure 1 except that the central support for the diaphragm is omitted and instead the diaphragm is supported at its periphery. For this purpose, a plurality of pillars 14 screwed into the housing 3 support a mounting ring 17. A diaphragm 16 is secured between the ring 17 and a clamping ring 18 which latter is secured to the pillars 14. The diaphragm 16 has an aperture 19 at the centre thereof.

50 The housing 3 shown in Figure 3 tapers towards the diaphragm 16 so that the underside face of the diaphragm 16 has free access to the surrounding air.

55 The microphones described above with reference to the figures, operate as follows. Sounds originating from a relatively distant source cause pressure waves to impinge simultaneously and substantially equally on the upper and under-sides of the diaphragm. The forces acting on 60 the upper and under-sides of the diaphragm are, therefore, substantially balanced and substantially no vibration of the diaphragm takes place. Hence substantially no electromotive force is generated in the coil 5. When sound waves emanate from a relatively close point source (for example, a person's mouth) above the microphone as seen in Figure 1 or 3, the pressure waves impinge upon the upper side of the diaphragm with greater intensity than they do on the under-side of the diaphragm. Hence the

65 forces acting on the diaphragm are unequal and the latter vibrates. The coil 5 moves with the diaphragm 7 or 70 16 as the case may be, and cuts magnetic lines of force

across the air gap 4, whereby an electromotive force is induced in the coil.

We claim:

1. A microphone comprising an effectively plane diaphragm, supporting means for the diaphragm permitting vibration of the latter, said means engaging the diaphragm over an area which leaves substantially the whole of the peripheral extent of the diaphragm substantially freely accessible to the atmosphere surrounding the microphone whereby both faces of the diaphragm become substantially freely accessible to the atmosphere surrounding the microphone, a coil supported from the diaphragm to move in correspondence with the vibration of the diaphragm, means for establishing a magnetic field whereby movement of the coil in the field causes an electromotive force to be induced in the wires of the coil, and the diaphragm having at least one aperture within the area covered by the coil, the arrangement thus being such that sound waves from a relatively distant source cause substantially no vibration of the diaphragm and sound waves from a relatively close source not in the plane of the diaphragm cause vibration of the diaphragm.

2. A microphone comprising an effectively plane diaphragm, both faces of the diaphragm being substantially freely accessible to the air surrounding the microphone over substantially the whole peripheral extent of the diaphragm, a coil of annular form supported from the diaphragm to move in correspondence with the vibration of the diaphragm, a pot-type permanent magnet having an annular air gap in which the coil is located, whereby movement of the coil causes an electromotive force to be induced in the wires of the coil, a support rigidly securing the central portion of the diaphragm to the central pole of the pot-type magnet, and the diaphragm

having a plurality of holes arranged in a ring around said support.

3. A microphone comprising an effectively plane diaphragm, both faces of the diaphragm being substantially freely accessible to the air surrounding the microphone over substantially the whole peripheral extent of the diaphragm, a coil of annular form supported from the diaphragm to move in correspondence with the vibration of the diaphragm, a pot-type permanent magnet of cylindrical form and having an annular air gap in which the coil is located, whereby movement of the coil causes an electromotive force to be induced in the wires of the coil, a support rigidly securing the central portion of the diaphragm to the central pole of the pot-type magnet, and there being recesses at the outer periphery of the magnet adjacent the diaphragm to provide free access of the surrounding air to the face of the diaphragm adjacent the magnet.
